United States Patent Office

Des. 186,469

Patented Oct. 27, 1959

186,469

HORIZONTAL BORING MACHINE

John D. Osborn, Houston, Tex., assignor to Gilbert M. Turner and William M. Horner, both of Houston, Tex.

Application August 18, 1958, Serial No. 52,276

Term of patent 14 years

(Cl. D55—1)

Fig. 1 is a rear perspective view taken from one side of a horizontal boring machine, showing my new design;

Fig. 2 is a side elevational view taken from the opposite side of Fig. 1;

Fig. 3 is a perspective view showing the side of Fig. 1 and the front; and

Fig. 4 is a front perspective view thereof.

I claim:

The ornamental design for a horizontal boring machine, as shown.
